UNITED STATES PATENT OFFICE

117,698

DESIGN FOR A BATTERY BOX

Oliver O. Rieser, Oak Park, Ill., assignor to The Richardson Company, Lockland, Ohio, a corporation of Ohio

Application March 13, 1939, Serial No. 83,549

Term of patent 7 years

To all whom it may concern:

Be it known that I, Oliver O. Rieser, a citizen of the United States and a resident of Oak Park, in the county of Cook and State of Illinois, have invented a new, original, and ornamental Design for a Battery Box, of which the following is a specification, reference being had to the accompanying drawing, forming a part thereof.

In the drawing:

The single figure in the drawing is a perspective view of a battery box showing my new design.

The other side and end portions of the battery box design are the same as the side and end portions shown in the drawing.

I claim:

The ornamental design for a battery box, substantially as shown and described.

OLIVER O. RIESER.
